ELECTRIC PLUG

Raymond McCutcheon, Chicago, Ill.

Application July 16, 1940, Serial No. 345,820

3 Claims. (Cl. 173—361)

My invention relates to electric plugs of the standard type employed in homes, offices, etc., for service from electric current outlets, and my main object is to provide a plug of this kind which can be attached to the cord or wiring without the use of screws or tools.

A further object of the invention is to provide an electric plug in which the terminals of the contacting wires are securely clamped.

Another object of the invention is to construct the plug with two prong units which are rigidly secured and braced against dislodgment or deviation from their proper positions.

An additional object of the invention is to design the novel plug with few parts which are simple and substantial, so that the plug may be inexpensively manufactured and depended upon to serve efficiently for a long time.

With the above objects in view and any others which may suggest themselves from the description to follow, a better understanding of the invention may be had by reference to the accompanying drawing, in which—

Fig. 1 is a vertical section of the plug;

Fig. 2 is a top plan view;

Fig. 3 is a group perspective of one of the terminal units;

Fig. 4 is a view similar to Fig. 5, showing a modification;

Fig. 5 is a perspective view showing a prong unit employed in the modification;

Fig. 6 is a section of a brace taken on the line 6—6 of Fig. 4; and

Fig. 7 is a bottom plan view of a portion of Fig. 6.

The attachment and use of electric plugs in homes, offices, etc., has in late years become familiar to the average mechanically inclined person, and it is a common occurrence for such persons to attach new plugs to electric light cords or replace defective plugs. In such cases, a screw-driver—and sometimes a pair of pliers—is needed to do the job. Also, the rough handling or the application of these tools when a plug repair or installation is made often loosens one of the terminals from the base to which it is attached by screws, rivets or eyelets. Often, the screws employed for the attachment of the wires often become jammed, making it difficult to release them; or, they become loose from the handling of the cord or appliance, so that the electrical contact or connection is impaired. It has therefore been my intention to depart from the deficiencies outlined above and provide a plug which contains no screws, rivets or eyelets, and

requires no tools for its installation or removal, so that even persons having no mechanical knowledge may easily learn to apply, repair or change a plug connection.

5 In accordance with the foregoing, specific reference to the drawing indicates a typical electric service cord at 10, and the current wires issuing therefrom at 11. The novel electric plug 12 has a body or casing similar to the conventional types of plugs, such casing having an opening 13 in the bottom for the entrance of the cord 10. The familiar type of metal prongs 14 extends from the casing in a manner to fit standard current outlets.

10 For the purpose of the present invention, each prong 14 is made with an integral segmental base 15 which is suitably attached or embedded in the stock 16a of the plug casing, whereby to permanently secure the same to the casing. It is understood that a pair of the prong units 14 is deposited in the casing in opposed relation, as suggested in Fig. 2, and amply spaced for the free approach or manipulation of the current wires 11 for purposes of attachment.

15 In the main embodiment of the plug, the base 15 of the prong unit is formed with a doubled arch 16 at one side of the prong, such arch having a transverse opening 17. The arch is intended to receive a sheet metal cap 18 which is adapted to fit over the arch and become tensioned as fitted, so as to snugly engage the arch. One side of the cap 18 is made with a bottom notch 19; and the material in the region of the notch is expanded to form an arched channel 20 in the center of the cap, such channel opening on the notch 19 at one end and extending to the bottom of the cap with the other end.

20 In the application of one of the current wires to the prong unit 14, it is customary to train the wire around the back of the prong, as shown in Figs. 1 and 2. The stripped terminal portion of the wire is now passed through the opening 17 in the arch 16, then trained upwardly to return over the arch and descend over the initial 25 portion. Now the cap 18 is applied with downward pressure, so that when the cap has been fully depressed to seat on the base 15 or close thereto, the initial portion of the stripped wire is found to have passed through the notch 19 and taken a looped course in the channel 20 to return and issue upon itself. Thus, the cap 18 not only forms a clamp to retain the stripped wire to the arch 16, but provides a clearance by way of the notch 19 and the channel 20 for the wire, so that the latter is individually clamped

and retained in place, this clamping and retention not impairing the snug and uniform fit of the cap 18 upon the arch 16. Thus, with these parts properly designed, a tight fit of the connection is attained, all without the use of any screws or tools.

In order that the alinement of the prongs 14 may be insured, I provide a block 21 of insulation material as a brace therefor. Thus, the block is made with two narrow vertical slots 22 for the slideable passage of the prongs 14, and the ends of the block are suitably sealed or pressed into the casing 12 so as to become rigidly attached thereto.

In the modification, the prong unit 14 is made without the arch 16, but uses the bracing block for the clamping of the wires. Thus, Figs. 4 and 5 show that the prong 14 is made with two vertically spaced openings 23 in the middle, and that the stripped wire 11 is looped through these. The bracing block 24 is in this instance made detachable and its vertical slots 25 are enlarged along the middle with opposed vertical channels 26 which commence a short distance from the top, as shown in Fig. 6. Thus, when the block is applied over the prongs 14 and slid down along the same, the looped wires 11 in the region of the openings 23 will be received in the opposed channels 26. It is understood that the fit of the slots 25 on the prongs and the channels 26 on the wires will be fairly tight in the present instance, in order to impart the action of a clamp to firmly press the wires to the prongs; and the endwise fit of the block 25 in the walls of the plug casing 20 will also be fairly tight, in order that the block may hold its place during the handling or use of the plug. Of course, it follows that the plug will be removable by hand with a limited amount of exertion in case a repair or replacement must be made.

It will be evident from the above description that I have provided an electric plug which is inexpensive to produce because of the elimination of screws, tapped receptacles therefor and other instrumentalities employed in plugs now on the market. It is simply necessary to firmly attach the prong units in the casing of the plug at the factory, this also applying to the bracing block 21 in the main embodiment of the plug.

Only one further part is required for the main form, this being a cap 18. As to the handling of the plug for application, repair or replacement, very little instruction is necessary to make the same familiar to the average person, so that these tasks can be accomplished readily as needed, without tools, and without calling a trained or mechanically inclined person for aid. The novel plug is thus an article which is simplified in construction and easily serviced by any person.

While I have described the main and modified forms of the invention along specific lines, various minor changes and refinements may be made without departing from their principle, and I desire to consider all such changes and refinements as coming within the scope and spirit of the appended claims.

I claim:

1. In an electric plug having a body of insulating material provided with a circuit wire passage, a terminal comprising a base flange secured in the plug body, a contact prong extending therefrom, said flange having a portion doubled upon itself at a point spaced from the prong and apertured to receive a circuit wire therethrough, and a metal cap detachably engageable over said doubled portion to confine therebeneath a wire when trained through and over said doubled portion.
2. The structure of claim 1, and said cap being internally channelled to engage over the wire in frictional binding contact with said doubled portion.
3. In an electric plug, a body provided with a circuit wire passage, a terminal comprising a base flange secured in the plug body, a retainer block of insulating material secured in the plug body over said flange, a contact prong extending from said flange through said block, said flange having a portion doubled upon itself at one side of the block and apertured to receive a contact wire therethrough, and a metal cap engageable over said doubled portion to confine thereunder and clamp against said portion a circuit wire trained through its aperture, said cap being of a length not greater than the thickness of said insulating block.

RAYMOND McCUTCHEON.
